COMMUNICATION OF INTELLIGENCE

Application filed April 18, 1925, Serial No. 24,037. Renewed November 16, 1928.

The invention relates to the communication of intelligence, and more especially to communication over long distances as in submarine cable telegraphy.

5 The object of the invention, generally stated, is to provide a code whereby the transmission of intelligence may be accomplished at a substantially greater speed than has heretofore been possible.

10 In the accompanying drawings I have shown diagrammatically examples of prior codal systems and also an example of the present system, as an aid to a clear understanding of the invention. Figure 1 is an example of a word as transmitted in accordance with the well known Baudot code shown graphically in a manner analogous to the usual graphic representation of the standard cable code shown in Fig. 2. Fig. 3 is a similar example illustrating the use of my code. Fig. 4 illustrates graphically the number of different combinations obtainable by variously arranging a plurality of signal units.

15 The communication of intelligence as now practiced consists in the transmission of signals electrically to represent the individual letters or characters of the alphabet. In the case of land telegraphy automatically operating mechanism is frequently employed, 20 using what is known as the Baudot code. In this code each letter or character signal is composed of a combination of five units, each of which units is represented by either a positive or a negative current impulse and 25 hence has one of two differentiating characteristics. Thirty-two of such five-unit signal combinations are provided, and these are distributed among the letters of the alphabet and other characters. There are no spaces 30 between the letter signals composing a word, but spaces between words are represented by a five-unit space signal having certain positive and negative characteristics. The automatic mechanism employed includes printing devices controlled by the electric current 35 impulses. Herein I have shown in Fig. 1 the positive and negative impulses as being characterized by waves or loops a and b positioned respectively above and below a zero line c . Inasmuch as each wave unit may be

said to occupy either of two different positions, this code is commonly referred to as a "two position code".

40 In cable or submarine telegraphy, the standard cable code, also known as the modified continental code is now employed. In this code, the letter or character signals are composed of varying numbers of units each having three possible characteristics instead of two as in the Baudot code. Thus the units are represented by current impulses of either positive, negative or zero polarity, the latter being effected by a neutral line condition. Referring to Fig. 2, the positive and negative characteristics a' and b' are employed to 45 represent the units composing letter or character signals, and the zero characteristic c' is employed to represent space units between letter or character signals. This code is therefore referred to as a "three-positioned" 50 code, having reference to the two positions above or below the zero line in the recorded message and the third position coincident with the zero line.

55 It will be apparent from the foregoing that in both the Baudot code and in the standard cable code, letter or character signals are employed each consisting of units having differentiating characteristics and arranged in predetermined combinations. In 60 each case the units are represented by electric current variations and such variations require in the actual transmission a certain time interval depending upon the speed of the apparatus. Thus, it will be seen that the 65 rate of communication is directly proportional to the number of units which must be employed in transmitting a given message. In the sense herein employed, a unit is the 70 time required for the transmission of either 75 a positive, negative or zero potential impulse.

80 As is well known, the cost of long telegraphic lines and associated equipment, including the initial cost, the interest, depreciation and maintenance cost is very great; 85 and obviously the cost increases in proportion to the number of signal impulses which it is necessary to transmit to represent a given message. In the case of submarine telegraphy, it has been estimated authoritatively 90 100

(see Milnor, Journal A. I. E. E. February, 1922) that the cost in the case of each trans-
Atlantic cable is approximately \$400,000 per
year for a cable 2000 miles in length. Fur-
thermore, the same authority estimates that
the standard cable code requires the use of
twenty-two units in spelling out the average
word. The use of such a large number of
units per word constitutes a serious limita-
tion on the speed or rate of communication,
and when the cost of the equipment is con-
sidered it is readily apparent that this is one
of the chief causes of the high cost of cable
communication.

15 It is the aim of the present invention,
therefore, to reduce the cost of telegraphic
communication through the medium of a
novel code which is capable of use with the
present cable equipment, and which renders
20 possible a substantial reduction in the time
required for transmission by employing a
substantially reduced number of units for the
average word. This method consists essen-
25 tially in providing for each word of a given
vocabulary an individual preconcerted sig-
nal.

Proceeding now to a more detailed con-
sideration of the method or system constitut-
ing my invention, I utilize, in providing the
30 desired number of signals, that principle of
mathematics by which it is established that
while a relatively small number of units hav-
ing different possible characteristics may be
35 arranged in a relatively small number of dis-
tinct combinations, the number of possible
combinations increases very rapidly as the
number of units employed increases, and as
the number of possible characteristics of the
units increases.

40 In the present instance I employ a three-
position code so that each signal may repre-
sent a word and also a space. The units em-
ployed for the word have two possible differ-
45 ent characteristics, viz, positive and negative
polarity, and the space unit has only one pos-
sible characteristic, viz, a neutral line con-
dition. The space unit, being thus specifi-
50 cally different from the word units, serves to
separate the word signals effectually regard-
less of the length of the latter. This is an
important feature of the invention because
it renders possible the use of short signals
55 for frequently used words and thus greatly
reduces the number of units necessary for the
average word.

In Fig. 4 I have shown the various possible
combinations which may be obtained by the
use of one unit, two units, and three units,
60 where each unit is represented by a positive
or negative current impulse and hence has
two different possible characteristics.

The following table by way of illustra-
tion indicates the number of combinations ob-
tainable from one unit up to a relatively
65 large number of units, as for example, seven-

teen, where each unit may have either of two
positions or characteristics.

Combinations (C_n) of two different kinds
of signal units taken n at a time.

N	$C_n=2^n$	Total C_1+C_2 etc. up to $C_n=2^{(n+1)-2}$ or the cumulative total of column 2.	70
1	2	2	
2	4	6	
3	8	14	
4	16	30	75
5	32	62	
6	64	126	
7	128	254	
8	256	510	
9	512	1022	
10	1024	2046	
11	2048	4094	
12	4096	8190	
13	8192	16382	80
14	16384	32766	
15	32768	65534	
16	65536	131070	
17	131072	262142	

It will be seen that the number of combina-
tions obtainable from a maximum number of
five units where all must be used is thirty-two.
But since signals having one, two, three and
four units respectively may also be used, the
number of combinations which becomes
available is equal to the sum of the combina-
tions of one, two, three, four and five. Thus
in addition to the thirty-two combinations
obtainable from a maximum number of five
units, it would also be possible to use sixteen
additional combinations obtainable from
four units; eight additional combinations
from three units; four additional combina-
tions from two units, and two additional
combinations from one unit, a total of sixty-
two combinations.

It can be shown mathematically that the
total number of combinations available for
assignment to signals of varying lengths
from a given maximum number of units, is
equal to $2^{(n+1)-2}$. In such a case, n is
the number of units employed for the word
and the added 1 is for the spaces. Thus if n
is 5, $2^{(5+1)-2}=62$. That the number of
combinations available increases rapidly as
the number of units employed increases will
be seen from the fact that where n is 9,
 $2^{(9+1)-2}=1022$; and where n is 17, $2^{(17+1)-2}=262,142$. By further increasing
the number of units the number of combinations
available may be made large enough to meet
any requirements.

In practicing my invention the number of
units to be employed may obviously be
varied as desired, but it is believed that a
maximum number of eighteen (seventeen
plus one for the space) will in any case be
ample, the number of combinations avail-
able in such a case being 262,142. However,
since the signals vary in length, the average
number of units necessary to be employed
per word would in any case be obviously
somewhat less than eighteen. Furthermore,
advantage is taken of the fact that a com-
paratively small number of words form a

large proportion of the words in common use. Thus by assigning to the words of the vocabulary which occur most frequently the shorter combinations, that is to say, those containing the smaller number of units, the average length, or the average number of units employed per word, is greatly reduced.

Probably the preferred method will in practice provide signal combinations for all comparatively common words, while words occurring rarely may be spelled out letter by letter. In such event, the combinations of two units, three units, four units and five units would be reserved for the letters of the alphabet.

An investigation made for the purpose of determining the approximate number of words in common use disclosed that in a file of ordinary incoming business correspondence containing approximately 60,000 words thirty-two words occurred 28,300 times and one thousand words occurred 54,300 times. Accordingly, assuming that the signal combinations involving up to five units be reserved for the letters of the alphabet, the signal combinations involving six units would provide for the thirty-two words which are used approximately 47% of the time; and the signal combinations involving from six to ten units would provide for the thousand words which are used approximately 91% of the time. From this it may be estimated that the average length of word in the case of plain or ordinary English is in the neighborhood of seven units, and since, as above indicated, the average number of units required per word in the case of the present cable code is about twenty-two, the saving effected by my invention is very substantial, being in the neighborhood of three to one. This saving is clearly apparent from the examples shown in Figs. 1 to 3. The word "house" is taken in each case as representing an average length word. As spelled out by the standard cable code (Fig. 2) it is shown as consisting of five letter signals employing with the spacing signals twenty-one units. As spelled out by the Baudot code it consists of five signals for the letters and one for the space or a total of thirty units. As represented by a single signal combination (including the space) in accordance with my invention, it may consist of, say, seven units.

From the analysis which has been made it is estimated that less than one-tenth of one per cent of the words used would fall outside a vocabulary of 60,000 words. Accordingly if the signal combinations available from sixteen units are assigned to the words of such a vocabulary of 60,000 words, a maximum number of eighteen units gives in addition approximately 200,000 signal combinations which are available for assignment to code words as distinguished from plain Eng-

lish words, there being 262,142 signal combinations available for use with all eighteen units, according to the formula 2^n plus 1) - 2, as above set forth. Any words falling outside such a vocabulary of 260,000 signal combinations may be spelled out letter by letter. It should be noted, however, that each signal, whether representing a word or a letter, includes a space unit so that no space signal need be used except where two words to be spelled out follow in succession.

Obviously signal combinations devised in accordance with my method may be assigned to the most frequently used words up to any desired number, the remaining words being spelled out in accordance with any preferred code. Thus in view of the fact that a comparatively small number of words form a large proportion of every-day language, it may be desirable to limit the assignment of word signals to a maximum of, say, fifty words which in the analysis of plain or ordinary English above referred to were found to occur 31,700 times among 60,000 words. This would represent a substantial saving over the system now in use of approximately fifty per cent. For example, according to the standard cable code, forty-four units would be required for two words (twenty-two being the average number of units per word), whereas if one of these words were represented by a codal combination according to this invention and the other spelled out by the standard cable code system, a total of only twenty-nine units would be required.

In the use of my method of communication, coding and decoding mechanisms, either partially or wholly automatic, may be provided or various mechanical aids employed. It is only necessary, however, to employ apparatus which is now available together with a suitable index or file containing the various codal combinations and the words represented thereby. Positive and negative impulses may be transmitted by the use of apparatus such as is in common use to represent the two kinds or characteristics of the units composing the words, and the neutral line condition may be effected also in accordance with known apparatus to represent spaces. It should be understood, however, that my code is not limited to use in line signaling. Thus it may readily be employed in radio communication. Also, the number of differentiating characteristics for the units may vary. For example, if transmission is effected by the well known carrier current method, different frequencies may be employed to indicate various characteristics and the number of such frequencies and hence characteristics may readily be more than three. This would greatly increase the number of possible combinations available from a small number of units.

The message may be received and graphically recorded by the use of the well known siphon recorder; and by the use of the index provided an operator decodes the message, translating the message represented graphically by a line (see Fig. 3) into a word message. As an aid to the decoding operation, apparatus operating wholly or partially automatically may here, too, be employed, but inasmuch as such coding and decoding apparatus form no part of this invention it is deemed unnecessary herein to describe the same.

It will be apparent that because of the substantial saving in time effected by the transmission of intelligence according to my invention as compared to the method now in common use, the time required for the decoding operation, even though purely manual, offers no serious obstacle. Thus it is probable that the additional coding and decoding cost per word as compared to the cost of present methods, would be nominal, and this cost can be very greatly reduced by the aid of the coding and decoding apparatus above referred to.

To reduce to a minimum errors due to the failure of the transmitting operator, messages to be transmitted, may, if desired, be checked before sending out without substantially increasing the cost; and to insure accuracy in the transmitting apparatus, it may be desirable to reduce slightly the speed of actual transmission. This may be done without a material reduction in the total saving of time effected.

It will be understood that while my invention has been specifically described with respect to the English language, it is applicable to any written language whatever. In practice, therefore, a suitable signal would be employed to indicate the particular language used. Furthermore, an identifying signal would be used to indicate the kind or character of code employed, that is to say, whether one or another of the common commercial codes is being used.

I claim as my invention:

In a telegraphic communication system in which signals each composed of a direct succession of units having two or more differentiating characteristics are transmitted electrically, the method of signalling which consists in transmitting word signals individually representing such words as fall within a given vocabulary, and transmitting letter signals individually representing letters of the alphabet and spelling out letter by letter such words as fall outside the given vocabulary, while composing all of said signals of code combinations of a variable number of units each including an invariable terminal unit, so that as the signals occur in direct succession with no space signals between them they are capable of being distinguished from

each other, and sending a space signal between the adjacent terminal letter signals of successive non-vocabulary words.

In testimony whereof I have hereunto affixed my signature.

DUNCAN J. STEWART.
